H. M. WILLIAMS.
GAS STOVE AND VENTILATOR.

(Application filed Oct. 9, 1897.)

(No Model.)

Fig. 1.

UNITED STATES PATENT OFFICE.

HENRY M. WILLIAMS, OF FORT WAYNE, INDIANA, ASSIGNOR OF ONE-FOURTH TO FRANZ BURGER, OF SAME PLACE.

GAS-STOVE AND VENTILATOR.

SPECIFICATION forming part of Letters Patent No. 630,017, dated August 1, 1899.

Application filed October 9, 1897. Serial No. 654,635. (No model.)

To all whom it may concern:

Be it known that I, HENRY M. WILLIAMS, a citizen of the United States, residing at Fort Wayne, in the county of Allen and State of Indiana, have invented certain new and useful Improvements in Gas-Stoves and Ventilators, of which the following is a specification.

This invention relates to certain new and useful improvements in combined gas or vapor heating-stoves and ventilators, having for its object to improve the construction and efficiency of such stoves generally; and the invention consists in the novel construction, combination, and arrangement of the parts hereinafter more particularly described.

In the accompanying drawings, forming a part of this specification, and in which like letters and numerals of reference designate corresponding parts, Figure 1 is a vertical sectional view of a stove embodying the invention. Fig. 2 is a horizontal sectional view on the line xx of Fig. 1. Fig. 3 is an enlarged sectional view of one of the heated air-columns. Fig. 4 is an enlarged detail sectional view of the damper controlling the flow of hot air from the generator to the discharge-flue.

Referring more particularly to the drawings, A designates the base of the stove, mounted upon suitable supports 1 and provided with an air-chamber 2. Formed in the bottom of said base is an inlet-opening 2^a, controlled by suitable sliding dampers 2^b.

Supported upon and extending above the base is an inverted conical hot-air generator B, the lower end of which extends centrally through the base and opens beneath the same, and surrounding said generator at its contracted end is an annular gas or vapor burner C, suitably mounted upon the base and connected with a supply-pipe 3. As shown, the wall of the generator is plain. It will be readily understood, however, that it may be formed with either annular or longitudinal corrugations, if desired.

Located above the generator B is an annular top D, formed with a hot-air-distributing chamber 3^a, which communicates with the interior of the generator through horizontal radial passages 4 and a vertical passage 5.

Surrounding the hot-air generator B is a

series of vertical air-columns E, which communicate at their upper ends with the air-distributing chamber 3^a and at their lower ends with the air-chamber 2 of the base A. 55 These air-columns may be arranged in close juxtaposition in order that the hot-air chamber or space 6 intermediate the columns and the air-generator may be practically a closed one; but preferably wide spaces are left between the columns, leaving the burner and generator exteriorly exposed in order that heat may be radiated into the room from the generator. The inner walls of the columns converge toward the hot-air generator B, and 65 upon their interior the columns are provided with longitudinal ribs 7, the purpose of which will be presently described.

Extending centrally through the top D is a cylindrical discharge-flue 8, which communicates at its lower end with the hot-air chamber 6 and at its upper end with a stovepipe 9, through which the products of combustion pass from the said chamber 6. The said flue also communicates with the upper end of the 75 passage 5.

Projecting from the exterior of a pipe 16, near the upper end thereof and above the radial passages 12, is an annular conical flange 16^a, which extends partially across the passage 5, and likewise projecting from the interior of the sleeves 10 is a corresponding flange 10^a. These flanges are so arranged that when the parts are in their normal positions, as shown in Fig. 1, they will rest in contact and 85 close the upper end of the passage 5, thereby directing the hot air through the radial passages 12 into the chamber of the top D. When, however, the sleeves 10 13 are lowered, the flange 10^a will be carried away from the flange 16^a and the air ascending through the generator and passage 5 will be permitted to flow into the discharge-flue 8.

The top D is preferably provided with perforations through which the hot air may escape from the air-distributing chamber 3^a; but, if desired, it may be formed with closed walls, or suitable pipes may be led from the distributing-chamber to convey the hot air to distant points.

Adapted to slide within the passage 5 is a sleeve 10, formed in its sides with openings

12, which normally register with the radial passages 4, and arranged within the lower end of the hot-air generator B is a similar open-ended sleeve 13, which is normally within 5 the generator, but is adapted to be projected below the base to bring its lower end in close proximity to the floor. The two sleeves 10 13 are connected together by means of rods 14, and to the lower sleeve is connected one end of a pivoted lever 15, by means of which the sleeves may be simultaneously raised or lowered.

It is a well-known fact that the foul air in a room by reason of its contained carbonic-acid gas falls to the floor of the room, and in order to prevent the flow of this vitiated air through the air-distributing chamber it is only necessary to lift the lever 15 and lower the sleeves 10 and 13 to close the radial passages 4 and bring the lower end of the sleeve 13 close to the floor, when the foul air will pass through the generator B, vertical passage 5, and out through the stovepipe. In order that the greater portion of the vitiated air may be constantly discharged, a pipe 16 is projected through the generator B, with its lower end normally in close proximity to the floor and its upper end extended into the top of the cylinder 8 above the plane of the radial 20 passages 4, and this pipe is likewise connected to the end of the lever 15 to be simultaneously operated with the sleeves 10 13.

From the above it will be understood, the parts being in the positions indicated in Fig. 35 1 and the burner being lighted, that the flames coming in contact with the exterior of the generator will heat the same as well as the air passing through it to the air-distributing chamber, and the heat from the generator 40 will be radiated into the room and to the air-columns, causing said columns and the air flowing through them to become heated also, the air being admitted to the passages of the 45 columns through the openings 2^a and air-chamber 2 of the base. By forming the columns with sides or walls which converge inwardly toward the generator the columns will be sufficiently heated to impart a high degree of heat to the air flowing through the columns; 50 but said converging walls will not obstruct the heat-rays and cause heat to be reflected back to the generator. On the contrary, the heat-rays which strike the converging walls of the columns will merely be slightly deflected and will flow into the room.

In mild weather when very little heat is required the stove may be surrounded by a screen of wire-netting, which serves to prevent the heat being radiated from the walls 60 of the hot-air generator into the room, the heat passing out through the discharge-flue. This screen may be constructed in any suitable manner which will permit it to be readily attached and detached from the stove, and it 65 is not deemed necessary to illustrate it.

Without limiting myself to the exact construction and arrangement of the parts shown

and described, since it will be understood that such construction and arrangement may be variously modified and some features of the 70 invention used without others,

What I claim is—

1. In a gas or vapor stove, the combination with a central hollow hot-air generator open at its lower end, of a burner surrounding the 75 generator, a hollow top above and overhanging the generator and communicating therewith, said top being formed with a discharge-flue surrounding the generator, and means for placing the discharge-flue into and out of 80 communication with the interior of the generator, substantially as described.

2. In a gas or vapor stove, the combination with a base, of a central hollow hot-air generator mounted upon the base, a burner surrounding the generator, a series of separated air-columns surrounding the generator and burner, the said generator and air-columns being open at their lower ends, a hollow top 85 above the generator communicating with the generator and with the air-columns and a central discharge-flue through the top, substantially as described.

3. In a gas or vapor stove, the combination with a base, of a central hollow inverted conical hot-air generator upon the base open at 95 its lower end, an exteriorly-exposed burner surrounding the generator at its lower end, a series of separated hollow air-columns surrounding the burner and generator, a top 100 supported above the generator, and a central discharge-flue extending through the top and leading from the space between the air-columns, substantially as described.

4. In a gas or vapor stove, the combination with the base, of a central generator upon the base, an exteriorly-exposed burner surrounding the generator at its lower end, a series of separated hollow air-columns open at their 105 lower ends, surrounding the burner and generator and having their inner surfaces converging toward the generator, a hollow top 110 above the generator communicating with the air-columns and a discharge-flue leading from said top and communicating with the space 115 between the air-columns, substantially as described.

5. In a gas or vapor stove, the combination with a base, of a central generator mounted upon the base, a burner surrounding the generator at its lower end, a series of hollow air-columns provided with internal longitudinal ribs and open at their lower ends, said columns surrounding the generator and burner and having their inner surfaces converging 120 toward the cone and a hollow perforated top 125 mounted upon the generator and communicating with the air-columns, substantially as described.

6. In a gas or vapor stove, the combination with a hollow base formed with air-inlet openings, of a central hollow hot-air generator mounted upon the base and open at its lower end, a burner surrounding the generator, a

series of hollow air-columns surrounding the burner and generator and communicating with the hollow base, a hollow perforated top mounted above the generator and communicating therewith and with the air-columns and a discharge-flue through the top leading from the space between the air-columns, substantially as described.

7. In a gas or vapor stove the combination 10 with a base and a hollow top, formed with a discharge-flue, of a hollow air-generator mounted upon the base open at its lower end and adapted to communicate with the hollow top and with the discharge-flue at its upper end, 15 means for closing the upper end of the generator, a burner surrounding the generator and a series of hollow air-columns surrounding the generator and burner, open at their lower ends and communicating with the hollow top at their upper ends, substantially as described.

8. In a gas or vapor stove the combination 20 with a base and a hollow top, formed with a discharge-flue, of a hollow air-generator mounted upon the base open at its lower end and communicating with the hollow top and with the discharge-flue at its upper end, a burner surrounding the generator and a series of hollow air-columns surrounding the generator and 25 burner, open at their lower ends and communicating with the hollow top at their upper ends, and means for controlling the communication between the generator and top, substantially as described.

9. In a gas or vapor stove, the combination 35 with a base, a central hollow hot-air generator mounted upon the base and open at its lower end, means for opening and closing the upper end of the generator, a hollow top mounted above the generator and communicating 40 therewith, said top being formed with a discharge-flue extending through it and likewise communicating with the generator and a foul-air-discharge pipe extending through and below the generator and into the discharge-flue 45 to a point above the chamber of the top, substantially as described.

10. In a gas or vapor stove, the combination 50 with a base, a central hollow hot-air generator mounted upon the base and open at its lower end, a hollow top supported above the generator and communicating therewith, said top being formed with a discharge-flue extending through it and likewise communicating with the generator at a point above the 55 chamber of the top, means for controlling the communication between the generator and top and a sleeve within the lower end of the generator adapted to be projected below the same, substantially as described. 60

In testimony whereof I have signed my name to this specification in the presence of two subscribing witnesses.
